UNITED STATES PATENT OFFICE.

THOMAS MCKEE, OF PORTLAND, OREGON.

PERFORATED AND OTHER SHEET MUSIC.

1,398,107.

Specification of Letters Patent. Patented Nov. 22, 1921.

Application filed May 20, 1909, Serial No. 497,156. Renewed July 29, 1920. Serial No. 399,888.

To all whom it may concern:

Be it known that I, THOMAS MCKEE, of Portland, in the county of Multnomah, and in the State of Oregon, have invented a certain new and useful Improvement in Perforated and Other Sheet-Music, and do hereby declare that the following is a full, clear, and exact description thereof.

My invention relates particularly to written or printed music, adapted for use in automatic piano players, in which perforated sheets are used, and having reference to the particular case of automatic piano players, my object, generally stated, is to enable the performer to have before him the music as ordinarily written, with all the marks of expression, and in case of vocal music, the words as well, so that the performer may render the particular piece according to the ordinary marks of expression written by the composer thereon, and in the case of vocal music the words may be read and sung to better advantage; and my object, apart from this particular case, is to render unnecessary the turning of pages or leaves, as in the case of music, as ordinarily written, and to avoid its being broken up into braces, and to these ends my invention consists in the sheet music having the characteristics of construction and arrangement hereinafter specified and claimed.

In the accompanying drawings, the figure is an elevation of an arrangement embodying my invention, adapted for automatic piano

players.

In the embodiment of my invention illustrated in the drawings, there are two parallel rollers 10, containing a long sheet 11 of paper or other suitable material, adapted to be unwound from one roller and wound upon the other, so that music 12 printed or written thereon in the usual manner upon staves shall pass horizontally in front of the performer, the rollers being arranged vertically so that the travel of the sheet is horizontally. Besides the instrumental music in the instance illustrated, there are words written or printed in the usual place between the two staves, and there are the usual marks of expression. Besides the staves upon the sheet, the sheet is provided with perforations 13, as is usual in automatic piano players, which pass over and coöperate with a tracker bar 14.

An important advantage of the association of music written or printed in the customary

manner with the perforated sheet, is that familiarity with music and the expression marks, as commonly written, is all that is necessary to enable the accurate and perfect rendition of a piece of music, and to one familiar with this, it can be done more satisfactorily than with the expression marks used on perforated music, especially since in the case of my invention the expression marks are associated with the ordinary form of musical notation; and in the case of vocal music, the words are immediately before the performer, so that they can be very easily and conveniently read. Should it be desired to render the music by playing in the ordinary manner upon the keyboard, it is necessary merely to suspend the automatic operation, and by proper motor or otherwise operate the sheet-moving apparatus, so that the music alone will be caused to pass before the player, and in this connection it will be seen that my invention has the very important advantage of making it unnecessary to turn any leaves because the music is moved continuously and automatically before the performer. It will be evident that my invention may be embodied in an arrangement in which the perforations shall be formed in one sheet and the ordinary musical notation written or printed on a separate sheet, and my invention extends to the writing or printing of music in the ordinary form of notation in a long or continuous sheet, so that it may be caused to pass before the performer. It will be noted that the perforations to secure the automatic operation of the instrument are in the sheet wholly to one side of the staves on which the music in ordinary notation is written or printed. By thus having independence of the perforations and the written or printed music, neither is required to be modified on account of the presence of the other on the sheet. The words of the song are, it is to be noted, as is usually the case, printed in the space between the two staves.

As a means of more accurately indicating the composer's idea respecting the expression of the music, than by means of the ordinary expression marks, I place upon the staves lines 15, pursuing a devious or tortuous course, indicating loudness, softness, acceleration, retardation, etc., the lines by their form or course, and by their position, accurately or exactly pointing out the places where the expressions sought or intended

are to be given. My expression lines can be either continuous or dotted or broken, and printed in colors if desired.

Having thus described my invention, what I claim is—

1. A keyboard musical instrument adapted for operation by perforated sheets, having a tracker bar and sheet-engaging rollers, said bar and rollers being supported above the keyboard with their longitudinal axes in planes that extend from front to rear of the instrument and from top to bottom thereof.

15 2. A musical instrument adapted for operation by perforated sheets having a tracker bar and sheet-engaging rollers, said bar and rollers being supported with their longitudinal axes in planes that extend from front to rear of the instrument and from top to bottom thereof, the tracker bar being situated substantially midway between the rollers.

25 3. A musical instrument adapted for operation by perforated sheets, having a tracker bar and sheet-engaging rollers, said bar and rollers being supported with their longitudinal axes in planes that extend from front to rear of the instrument and from top to bottom thereof, in combination with a sheet having perforations, and music thereon in the ordinary form of notation comprising a staff or staves and music characters thereon, said staff or staves running longitudinally of the sheet in the direction of travel thereof across the tracker bar, said sheet passing over the tracker bar in a direction from side to side of the instrument, with the top edge of the sheet in a plane substantially higher than the bottom edge.

30 4. A musical instrument adapted for operation by perforated sheets, having a tracker bar and sheet-engaging rollers, said bar and rollers being supported with their longitudinal axes in planes that extend from front to rear of the instrument and from top to bottom thereof, in combination with a sheet having perforations, and music

35 thereon in the ordinary form of notation comprising a staff or staves and music characters thereon, said staff or staves running longitudinally of the sheet in the direction of travel thereof across the tracker bar, said

sheet passing over the tracker bar in a direction from side to side of the instrument.

4. A musical instrument adapted for op-

eration by perforated sheets, having a tracker bar and sheet-engaging rollers, said bar and rollers being supported with their longitudinal axes in planes that extend from front to rear of the instrument and from top to bottom thereof, in combination with a sheet having perforations, and music thereon in the ordinary form of notation, comprising a staff or staves and music characters thereon, said staff or staves running longitudinally of the sheet in the direction of travel thereof across the tracker bar, said sheet passing over the tracker bar in a direction from side to side of the instrument, with the top edge of the sheet in a plane substantially higher than the bottom edge.

5. The combination of a musical instrument adapted for operation by perforated sheets, and having upstanding sheet supports between which the sheet travel horizontally, and a sheet having lengthwise of it, lines of perforations and music in the ordinary form of notation consisting of a staff and notes thereon, and corresponding with the music represented by the perforations, the music in the ordinary form of notation being situated on the sheet vertically substantially wholly to one side of the portion of the sheet having the lines of perforations, the staff thereof extending lengthwise of the sheet.

In testimony that I claim the foregoing I have hereunto set my hand.

THOMAS MCKEE.
